UNITED STATES PATENT OFFICE.

AUSTIN F. JACKSON, OF TAUNTON, MASSACHUSETTS, ASSIGNOR TO REED
& BARTON, OF SAME PLACE.

DESIGN FOR A HANDLE FOR SPOONS AND FORKS.

SPECIFICATION forming part of Design No. 14,323, dated September 25, 1883.

Application filed July 14, 1883. Term of patent 7 years.

To all whom it may concern:

Be it known that I, AUSTIN F. JACKSON, of Taunton, in the county of Bristol and State of Massachusetts, have invented and produced a new and original Design for a Handle for Spoons, Forks, and Similar Articles, of which the following is a specification, reference being had to the accompanying photograph, forming part thereof, in which is shown a top view 10 of my newly-designed handle.

My design consists of a handle for spoons, forks, and similar articles, having its outer end representing hammered work, and its upper surface ornamented with a spray or sprays 15 of roses, which overlap the inner corners of the hammered work, and a flower and leaf and an insect, which are arranged, respectively, in the outer corners of the extension representing hammered work.

20 A indicates the handle, and B the piece representing hammered work, which is approximately square, and has the appearance of being an addition or extension to the handle. This piece is bounded by the slightly-concave

edges C and groove D. On the upper surface 25 of the handle is a raised imitation of rose-sprays, E E', the blossoms of the latter overlapping the inner corners of the piece B, and in the outer corners of said piece are the flower and leaf F and the insect, a common house-fly, G.

What I claim is—

1. The design herein shown and described, consisting of the handle having an extension representing hammered work, and an imitation of a spray of roses overlapping said extension. 35

2. The design herein shown and described, consisting of the handle having an approximately square piece or extension representing 40 hammered work, and imitations of rose-sprays overlapping the inner corners, and of a flower and leaf, and of an insect arranged in the outer corners of said piece.

AUSTIN F. JACKSON.
